TACK BUTTON

Frederick H. Peterson and Rollin R. Clarke, Waterbury, Conn., assignors to The Patent Button Company, Waterbury, Conn., a corporation of Connecticut

Application January 3, 1939, Serial No. 249,135

6 Claims. (Cl. 40—20)

Our invention relates to new and useful improvements in tack buttons, and more particularly to a tack button that may be quickly and readily oriented in a special button-attaching machine, as shown and described in an application filed by Frederick H. Peterson on the 12th day of December, 1938, Serial Number 245,278, for Orienting button-attaching machine. One of the objects of the present invention is to provide a button of the type shown in the application of Forrest G. Purinton, William A. Zwiebel, and Harold A. Verzier, for Tack button, filed on the 3rd day of January, 1939, Serial Number 249,138, wherein a tack of a greater diameter than the bore of the hub is to be driven into the button head for the purpose of attaching and to further arrange and so form the button that it may be quickly and readily oriented in a button-attaching and orienting machine.

Another object of the invention is to provide a button having an integral hub with flats on its opposite sides and a notch or aligning wall formed in its end, so that the button, when placed in a special hopper, may pass from the hopper and down the raceway to the attaching station in one and only one position, which position is in conformity with the insignia or brand or trademark formed in its top or upper face. As is well known to those skilled in the art, tack buttons which are used on overalls and work clothes generally have insignia or a trade-mark or a fanciful design on their top, and the button, when attached to the bib of the overalls or the work coats, should have the insignia in a readable position rather than upside down or at an angle to the eye of the observer.

A further object of the invention, therefore, is to provide a solid metal button having insignia on its face, which bears a certain relation to flats and aligning walls formed on the hub, so that when placed in a special button-attaching machine, the button will be attached to the goods in its properly oriented position.

With these and other objects in view, the invention consists in certain new and novel features and combination of parts, as will be herein-after more fully explained and pointed out in the claims.

Referring now to the drawing showing a preferred embodiment:

Fig. 1 is a side elevation of a fastener;

Fig. 2 is a bottom plan view thereof;

Fig. 3 is a bottom plan view of the button head;

Fig. 4 is a sectional view thereof;

Fig. 5 is a sectional view showing the button attached;

Fig. 6 is a face view showing the button as attached to the bib of an overall; and

Fig. 7 is a fragmentary view showing how the button is released from the hopper of a button-attaching machine to its attaching station, when in its oriented position.

It will be understood at the outset that the hereinafter described button head is similar in its broadest aspects to the button shown and described in the application of Forrest G. Purinton, William A. Zwiebel, and Harold A. Verzier, for Tack button, filed on the 3rd day of January, 1939, Serial Number 249,138, which, however, was not arranged for orienting purpose.

It will also be understood that possibly a button with a different form of attachment or fastener might be used, although we have found the one illustrated is preferable. Again, die-cast buttons or solid metal buttons have a special adaptability to the present invention, because the various flats and aligning walls may be formed in the button at the time the same is cast, thus doing away with any machine work, which is prohibitive in cost in buttons of this type.

Referring now to the drawing, and for the moment to Figs. 3 and 4, there is shown a solid die-cast button, preferably of a zinc alloy, having the head per se 1 and the integral hub 2. The insignia 3 or a fanciful design is also preferably cast in the button.

The hub is provided with the straight bore 4, into which the tack fastener is to be driven, as will be shortly described.

It will be noticed, also, that the hub, as shown in Fig. 3, is flattened on its one side, as at 5, and on its opposite side, as at 6, while extending parallel with the flat 6 is the cut-away portion or notch 7 to form what I term the aligning wall 8.

From Fig. 6, it will be seen that the insignia 3 bears a definite relation to the two flats 5 and 6 and also to the aligning notch 7 cut in the upper edge of the hub and the wall 8.

Although other forms of fasteners might be used, the one shown in Figs. 1 and 2 is preferable, which consists of the head 9 and the prong 10 with its flutes 11. Over the head of the tack is placed a small cap 12 for neatness of appearance.

The prong of the tack is also preferably japanned and of slightly greater diameter than the bore 4 of the button, so that when the same is driven into the bore, it will slightly expand the walls about the bore and then grip the prong.

with a resistant pressure, which is far greater than has been found necessary in button attachments.

In Fig. 7, there is fragmentarily shown the manner in which the button may be properly oriented in a button-attaching machine of the type shown in the application of Frederick H. Peterson, for Orienting button-attaching machine, filed on the 12th day of December, 1938, Serial Number 245,278.

Briefly, the hopper for orienting the buttons consists of a base plate 13, on which the button rests, while the hub of the button can only pass through the groove 14 when the one flat 5 is opposite the wall 15 and the other flat 6 is in contact with the wall 16, and the aligning notch 7 and the wall 8 register with the corner 11. It will be remembered that the button is in an inverted position when in the groove 14 of the hopper and then passes down a chute (not shown), where it is turned over rightside up, so that the reading matter or insignia 3 will be in the position as shown in Fig. 6 and the aligning notch 7 will be to the left.

When the button is formed this way with the two flats and the aligning wall as shown, it can only pass through the hopper when in its properly oriented position, and this position will be retained in the button-attaching machine (not shown) until it arrives at the attaching station, where it is forced down on the tack, which, in turn, will have pierced the goods and be driven up into the bore of the hub.

From the foregoing, it will be seen that we have provided a button, wherein the insignia bears a definite relation to the two flats and the notch and aligning wall, so that the button may be readily and quickly oriented in a button-attaching and orienting machine.

Furthermore, the button is one that is relatively inexpensive to manufacture and durable and efficient in service.

Having thus described our invention, what we claim as new and desire to secure by Letters Patent is:

1. A button head capable of being oriented hav-

ing indicia or the like on its face, an integral hub, flats formed on the hub, and the end of the hub having a defining wall formed therein parallel with the flats and bearing a definite relation to the indicia.

2. A solid metal button capable of being oriented having indicia on its face, a hub adapted to receive a fastener, the opposite sides of the hub being flattened, a groove formed in the end of the hub and to one side thereof and parallel with said flats to form an aligning wall for orienting purposes, and the said wall bearing a definite relation to the said indicia.

3. A tack button capable of being oriented having indicia or the like on its face, an integral circular hub and a flat portion on the side thereof, the lower end of the hub having a notch formed therein to provide an aligning wall when the button is in the orienting machine, and the aligning wall and flat bearing a definite position with relation to the indicia.

4. A solid metal tack button capable of being oriented including a head with indicia thereon and an integral circular hub, one side of said hub being flattened, the lower end of the hub having an aligning wall extending below the normal end surface of the hub and bearing a definite relationship to the flat and to the indicia on the button head.

5. A button head having an integral hub, flats on its opposite sides, a notch formed in the end of the hub parallel to the flats to provide an aligning wall, indicia on the face of the button head and extending at right angles to said aligning wall.

6. A metal tack button capable of being oriented having a hub, said hub provided with a bore to receive a fastener, a notch in the end of the hub to one side of the bore to form an aligning wall, flats on the sides of the hub one of which is beneath said aligning wall, and indicia on said button head and extending at substantially right angles to said aligning wall.
